US0D1035646S

(12) **United States Design Patent** (10) **Patent No.:** **US D1,035,646 S**
(45) **Date of Patent:** **** Jul. 16, 2024**

(54) **COMPUTER**

(71) Applicant: **Dynabook Inc.**, Tokyo (JP)

(72) Inventor: **Tomoaki Kimura**, Sakai (JP)

(73) Assignee: **DYNABOOK INC.**, Tokyo (JP)

(**) Term: **15 Years**

(21) Appl. No.: **29/790,112**

(22) Filed: **Nov. 5, 2021**

(30) **Foreign Application Priority Data**

May 6, 2021 (JP) 2021-009490D

(51) **LOC (14) Cl.** **14-02**

(52) **U.S. Cl.**

USPC **D14/318; D14/315**

(57) **CLAIM**

The ornamental design for a computer, as shown and described.

DESCRIPTION

FIG. 1 is a front, right, top perspective view of a computer showing the new design in a closed configuration;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear, left, top perspective view thereof.

FIG. 9 is a front, right, top perspective view of the computer of FIGS. 1-8, shown in an open configuration;

FIG. 10 is a front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is a rear, left, top perspective view thereof.

The broken lines in drawings show portions of the computer that form no part of the claimed design.

1 Claim, 14 Drawing Sheets
